United States Patent Office

Des. 215,911
Patented Nov. 4, 1969

215,911

TEXTILE FABRIC

Leonard C. Clementi, Huntington, N.Y., assignor to Cannon Mills Company, Kannapolis, N.C., a corporation of North Carolina

Filed Nov. 25, 1968, Ser. No. 14,623

Term of patent 14 years

Int. Cl. D5—02

U.S. Cl. D92—1

Ezg-1

FIG-2

FIGURE 2 is an enlarged top plan view of one repeat of the design and corresponding substantially to that area enclosed within the dotted lines of FIGURE 1.

I claim:

The ornamental design for a textile fabric, substantially as shown and described.
